[57] CLAIM

The ornamental design for a teacart, as shown and described.

DESCRIPTION

FIG. 1 is a front perspective view of a teacart showing my new design;

FIG. 2 is a front elevational view, the rear being a mirror image thereof;

FIG. 3 is a top plan view thereof;

FIG. 4 is a right side elevational view, the left side being a mirror image thereof; and

FIG. 5 is a front elevational view of a second embodiment of the teacart shown in FIG. 1.
